CLAIM

The ornamental design for a wheelbarrow handle grip, as shown and described.

DESCRIPTION

FIG. 1 is a perspective view of the wheelbarrow handle grip showing our new design;

FIG. 2 is a right end elevational view thereof;

FIG. 3 is a left end elevational view thereof;

FIG. 4 is a front elevational view thereof, the rear elevational view being a mirror image of the view shown in the Figure;

FIG. 5 is a top plan view thereof; and,

FIG. 6 is a bottom plan view thereof.
